HYDRAULIC POWER TRANSMISSION FOR
PRESSES

Robert Von Rotz, Manhasset, N. Y.

Application May 14, 1943, Serial No. 487,904

2 Claims. (Cl. 60—52)

My invention relates to hydraulic transmissions for presses of the rapid reciprocating head type used for continuous punching and shearing operations in connection with the stamping and forming of articles from sheet metal, leather, plastics, and like materials.

In mechanical presses of this class, the reciprocating head is generally driven by a crank and connecting rod in combination with a continuously rotating fly-wheel and clutch. With this arrangement, the actual pressure developed on the material is uncertain. The mechanical parts of the press are subject to high indeterminate loads and stresses which result in rapid wear, and frequent mechanical failures.

In conventional hydraulic presses of this class, a relatively large capacity pump in combination with a reversing valve is commonly used to reciprocate the head by means of a cylinder and piston. In this arrangement the maximum operating pressure is required only over a very small portion of the stroke cycle, consequently the hydraulic power transmission equipment is usually large and cumbersome, and due to the nature of the operating cycle, functions at relatively low efficiency.

It is the purpose of this invention to provide a combination of hydraulic and mechanical elements which embody a unique power transmission system as applied to a press which will be capable of delivering pressure strokes at high speed, and of a definite and uniform pressure intensity.

Another object of this invention is to provide an improved means for starting, stopping and timing the strokes of the press by simple hydraulic control valves.

These objects are attained by the mechanisms illustrated diagrammatically in the accompanying drawing, and described herein.

Figure 1 illustrates a more or less schematic embodiment of the hydraulic transmission made in accordance with the present invention.

Figure 2 is a detailed showing in section of the distributor valve 21, included in Figure 1.

Figure 3 is a detailed showing in section of the distributor valve 27, included in Figure 1.

Having reference to Figure 1, a platen or head 1 is attached to piston rod 2 slidable in cylinder 19 and free to move in response to fluid pressure on piston 29.

The piston rod 2 is recessed to receive part 17 having a central opening 20 to admit fluid to chamber 28.

Cylinders 4 and 5 with their respective plungers

6 and 7 comprise a high pressure pumping unit. The adjacent ends of these plungers are provided with rollers which abut cam 16. This cam is rigidly attached to rotatable shaft 22 carried in suitable bearings not shown. A flywheel M is keyed to shaft 22, and is caused to rotate by an external source. Springs 23 and 24 maintain the plungers in contact with the cam 16 at all times.

It is obvious that as flywheel M, shaft 22 and cam 16 are caused to rotate by any suitable prime mover, plungers 6 and 7 are caused to reciprocate alternately. Fluid thus drawn from reservoir 3 thru check valves 8 and 25 is directed to opposite ends of cylinder 19 thru conduits 13 and 26.

15 Numeral 11 represents a low-pressure rotary pump of any suitable construction, and 12 an adjustable pressure relief valve of any suitable type. Numeral 3 represents a storage reservoir for the hydraulic fluid, usually oil. In direct communication with the reservoir 3 is a pressure responsive shut off valve 8 of conventional type. This valve operates to control the flow of fluid between the lower part of cylinder 19 and the reservoir 3 through conduit 13. Fluid under pressure for 20 the opening and closing of valve 8 is provided by the low pressure pump 11.

A mechanically operated distributing valve 21 is arranged to control the application of fluid under pressure from pump 11 to valve 8 so that 25 actuation of valve 21 controls the flow of fluid between conduit 13 and reservoir 3 through valve 8. Valve 21 is arranged to be actuated by a cam, not shown, attached to shaft 22 in such a manner that rotation of shaft 22 and the cam causes 30 pressure to be directed to valve 8 so as to maintain it in the open position at all times except during the upward or pressure stroke of plunger 6. During the pressure stroke of plunger 6, valve 21 is actuated by the position of said cam so as to 35 close valve 8.

40 Valve 10 is an adjustable pressure relief valve of conventional type which is in communication with line 28 through conduit 33 and is connected to line 15 through conduit 34. Valve 32 is an 45 adjustable pressure relief valve of similar construction which is connected to line 35 through conduit 36 and to line 15 through conduit 37. Pressure from pump 11 through supply line 38 50 is directed to the pressure operated shut off valve 8 by distributing valve 27 through conduits 38 and 39. Exhaust fluid from valve 8 is directed to return line 15 through distributor valve 27 and conduit 31. Pressure from pump 11 is directed to distributing valve 21 through conduit 46. 55 Valve 21 is in communication with chamber 28

through passage 28 and conduits 41 and 45. Valve 21 is also connected to line 26 through conduit 42. Valve 9 is a check valve of conventional type which permits flow in one direction only, namely, from line 15 through conduit 43 to line 28. Check valve 25 of similar construction permits flow from line 15 to conduit 35 through line 44, but prevents flow in the reverse direction. Valve 12 is an adjustable pressure relief valve. Cylinder 19 is of the double acting differential type, having a relatively small effective piston area at the rod end and a large effective area at the head end. With the arrangement shown a relatively long opening stroke of the piston is obtained with a small displacement of fluid.

The operation of my mechanism is as follows:

Fluid under low pressure from pump 11 is directed thru conduit 20 to chamber 28 so as to exert pressure on piston rod 2 tending to urge it upward. Pressure is therefore developed on the fluid in the rod end of cylinder 19, conduit 26, and the chamber of cylinder 8. As cam 16 rotates counter clockwise from the position shown, plunger 7 is displaced so that high pressure fluid is directed to the rod end of cylinder 19. Piston rod 2 is thus caused to move downward. Fluid from the opposite end of the cylinder is displaced thru conduit 13 and valve 8 which is open. Fluid from chamber 28 together with the low pressure pump delivery is displaced thru relief valve 12 to reservoir 3. As the cam 16 continues to rotate, plunger 1 is displaced by spring 24 so that oil from the rod end of cylinder 19 is withdrawn permitting the head 1 to rise and contact the work 18 in response to the pressure maintained in chamber 28.

As shaft 22 rotates further, valve 27 is actuated so as to close valve 8. The further rotation of cam 16 displaces plunger 6 so as to direct fluid under high pressure thru conduit 13 to the head end of cylinder 19 causing the platen 1 to advance and perform the desired operation. During this portion of the operating cycle, the kinetic energy stored in the flywheel is utilized to develop a high fluid pressure in cylinder 4 which is transmitted by the means indicated to the work. As cam 16 continues to rotate, spring 23 displaces plunger 6 so as to draw in fluid from reservoir 3 thru check valve 25.

This cycle is repeated as long as flywheel M with shaft 22 and cam 16 are caused to rotate, and valve 21 is shifted to direct pressure from

pump 11 to chamber 28. It is apparent that there will be one complete operating cycle for each revolution of the flywheel.

When valve 21 is manually shifted so as to direct pressure thru conduit 26 to the rod end of cylinder 19, the press is maintained in the open position as may be required for setting up, adjusting or loading.

This invention is not intended to be limited to the form shown in the drawing which is understood to be illustrative and diagrammatic only.

I claim:

1. In a hydraulic power transmission mechanism, pump plungers mounted to slide in cylinders, and arranged to be reciprocated in said cylinders by a rotating cam, and adapted upon their movement to displace a liquid, a shaft arranged to be rotated by an external power source, a flywheel and cams attached to said shaft and disposed to impart reciprocating motion to said plungers in opposite phase relationship by its rotation, a work cylinder with a piston and piston rod mounted to slide in said cylinder and conduits connecting the pump cylinders with opposite ends of the work cylinder, an auxiliary pump driven by an external power source to supply fluid at low pressure to rapidly advance the work slide, a hydraulic fluid reservoir with a conduit connecting said reservoir to said work cylinder, a cut-off valve between said conduit and said reservoir arranged to be operated in timed relation to the working strokes of the piston.

2. In a hydraulic power transmission mechanism, a high pressure pump comprising plungers, 35 slideable in cylinders and adapted to be driven in opposite phase relationship by a cam attached to a rotary shaft, a differential work cylinder having a work piston provided with a supplementary expansible chamber for low pressure fluid, 40 a low pressure pump for supplying fluid to said chamber to rapidly advance the work piston, a cut-off valve in the work cylinder conduit to confine the high pressure during the working stroke, a timing valve for directing fluid to the cut-off 45 valve in timed relation to the power strokes of the piston, a manually operated distributing valve arranged to direct delivery of the low pressure pump to the work cylinder for starting and stopping the automatic operation of the piston at the will of the operator.
